GREASE GUN FILLER

Arthur Lee, Kankakee, Ill.

Application February 25, 1937, Serial No. 127,727

6 Claims. (Cl. 221—79)

This invention relates to apparatus for use in filling grease guns with lubricant.

As is well known to those skilled in the art, lubricating grease is sold usually in cans. An object of the present invention is to provide simple, efficient and compact means whereby the contents of a can, can be discharged therefrom at will and in controllable quantities for the purpose of filling a grease gun or the like when necessary.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred forms of the invention have been shown.

In said drawings:

Figure 1 is a side elevation of the apparatus showing a lubricant containing can in position therein ready for delivery of its contents.

Figure 2 is a front elevation.

Figure 3 is a top plan view.

Figure 4 is an enlarged section on line 4—4, Figure 1.

Figure 5 is a section on line 5—5, Figure 4.

Figure 6 is a side elevation of the apparatus showing the parts positioned during the application of the filled can thereto.

Figure 7 is a section through a slightly modified form of head which can be used with the apparatus.

Referring to the figures by characters of reference 1 designates a tubular socket having diverging legs 2 and 3 for supporting it in a substantially vertical position. This socket is provided with one or more set screws 4 or similar devices for the purpose of fastening the lower end of a standard 5 within the socket.

Adjustably mounted on the standard 5 near one end is a sleeve 6 having a set screw 7 or the like whereby the sleeve can be held in any position to which it may be moved along the standard. This sleeve is located at the outer end of an arm 8 which is made integral with a head 9 the diameter of which is somewhat greater than that of the bottom of the can C to be used in the apparatus. The bottom of the head can be provided with a gasket 10 of cork or any other suitable material adapted to fit snugly against the bottom of the can C and, if desired, a circular

recess 11 can be formed in the bottom of the head to receive the bead c usually formed around the bottom of a can. Thus it will be seen that head 9 can be caused to fit snugly against the bottom of an inverted can as shown particularly in Figure 4.

Extending through the head 9 at the center thereof is an opening 12 the upper end of which is normally closed by a screw plug 13 or other removable and tight fitting closure. A by-pass 14 extends within the head from this opening to a nozzle 15 located beyond the head and supported thereby. The outlet end of this nozzle can be closed normally by a cap 16.

In the structure shown in Figure 4 the nozzle 15 is made up of tubular members detachably connected to one side of the head but it is to be understood that, if desired, the by-pass, as shown at 17 in Figure 7, can be extended within a downwardly turned arm 18 integral with the head and into which the depending nozzle 19 is inserted.

Mounted on the standard 5 near that end remote from the sleeve 6 is another sleeve 20 which can be held in any desired position on the standard by means of a set screw 21 or the like. An arm or bracket 22 is extended from this sleeve and has a bore 23 within which is slidably mounted a screw 24 engaged by an adjusting wheel 25. This wheel bears against the bracket 22.

Screw 24 is aligned with the opening 12 in head 9 and that end nearest the head is preferably angular in contour, as shown at 26 and seated within superposed disks 27 and 28 which are clamped upon a cup-like disk 29 of rubber or other suitable material the marginal portion of which is extended toward head 9 and is adapted to frictionally engage the inner surface of a can C when placed in the apparatus. The disks 27 and 28 are held in firm contact with the interposed disk 29 by a nut 30 engaging a threaded stud 31 projecting from the end of screw 24.

Mounted on the standard 5 between the sleeves 6 and 20 is a split sleeve 32 having spaced arms 33 extending from the ends thereof and joining them to opposed edge portions of a band 34. This band is so proportioned as to fit snugly around the container C and, when the arms 33 are drawn toward each other by means of a tie-bolt 35, the band will clamp tightly on the inserted can and hold it against radial expansion when subjected to pressure from within.

When it is desired to use this apparatus for the purpose of dispensing grease from a can, the standard 5 is removed from the position shown

in Figure 1 and inverted so that the end which was formerly uppermost, can thus be inserted downwardly into the socket 1 and fastened, as shown in Figure 6. Thus head 9 will be brought 5 to position below the follower formed by disks 27, 28 and 29. The can C containing the grease to be dispensed, is placed with its open end uppermost on the inverted head 9 and within the reenforcing band 34. The bail generally supplied with the can for use as a handle, is removed from the opposed sockets d usually provided on the can and the laterally turned upper ends 36 of tie-rods 37 are inserted into these sockets. The other ends of the rods, which are 10 screw threaded, are inserted through ears 38 at the margin of the head 9. By means of nuts 39 engaging these threaded ends, the rods are drawn tightly so as to bind the bottom of the can against the head.

20 After the can has thus been placed in position the follower made up of the disks 27, 28 and 29, is lowered into the open end of the can so that the marginal portion of disk 29 will hug closely to the inner surface of the wall of the can.

25 The follower is held in this position by adjusting the wheel 25 against the bracket 22. Band 34 is tightened about the can so as to hold it against expansion under pressure from within and standard 5 is then removed from socket 1, reversed, 30 and its other end inserted into the socket so that the parts will thus be positioned as shown in Figures 1, 2 and 3.

The operator next removes the plug or other closure 13 and, by means of any suitable tool 35 inserted downwardly through the opening 12, punctures the bottom of the inverted can C. The plug or closure 13 is then replaced and the apparatus is ready for use.

When it is desired to withdraw a portion of 40 the contents of the can, the cap 16 is removed and the grease gun or the like is attached to the nozzle 15. The follower is then fed upwardly toward the head 9 and within the can and will cause a portion of the grease to be expelled 45 through opening 12 and by-pass 14 to nozzle 15 and thence to the grease gun.

Importance is attached to the provision of the 50 reenforcing band 34 which serves to prevent the can from bursting while being subjected to pressure.

What is claimed is:

1. A grease dispenser including a base, an invertible standard detachably mounted at either end in the base, an apertured member thereon, 55 a delivery nozzle carried by said member and communicating with the aperture, a follower, means on the standard for adjustably supporting the follower for movement toward said member, and means on the standard for surrounding and gripping a grease container with its bottom 60 against the apertured member and its open end positioned to receive the follower.

2. A grease dispenser including a base, an invertible standard detachably mounted at either 65 end in the base, an apertured member thereon,

a delivery nozzle carried by said member and communicating with the aperture, a follower, means on the standard for adjustably supporting the follower for movement toward said member, and compression means on the standard for surrounding and gripping a grease container and holding it with its bottom against the apertured member and its open end in position to receive the follower.

3. A grease dispenser including a base, an invertible standard detachably mounted at either end in the base, a member thereon having an aperture for the reception of a puncturing tool, a removable closure for the aperture, a delivery nozzle carried by said member and communicating with the aperture, means for holding a container with its bottom thrust against said member in position to be perforated by a tool inserted into the aperture, means on the standard for surrounding and gripping the container, a follower, and means on the standard for supporting the follower in position for insertion into the open end of the container.

4. A grease dispenser including a supporting structure, a reversible standard having both ends proportioned to be detachably seated in said structure, a member on the standard having an aperture for the reception of a puncturing tool, a removable closure for the aperture, a nozzle carried by said member and communicating with the aperture, means for securing a filled container in position with its bottom thrust against the apertured member to receive a puncturing tool, a follower, and means connected to the standard for adjustably supporting said follower for movement into the held container.

5. A grease dispenser including a base, an invertible standard detachably mounted at either end in the base, a member thereon apertured for the reception of a puncturing tool, a nozzle carried by said member and communicating with the aperture, a removable closure for the aperture, a follower adjustably supported on the standard for movement toward or from said member, means for attaching a container to the member with its bottom in position to be perforated by a puncturing tool when inserted into the aperture, and adjustable means for embracing the supported can for holding it against expansion under internal pressure, said means being carried by the standard.

6. A grease dispenser including a member having an aperture for the reception of a puncturing tool, a nozzle carried by said member and communicating with the aperture, a removable closure for the aperture, means for securing a grease container to said member with its bottom in position to be perforated by a puncturing tool inserted through the aperture, an adjustable follower positioned for movement into a held container, a connection between the follower and the apertured member, and means on said connection for surrounding the held container to prevent bursting.

ARTHUR LEE.
